(57) **CLAIM**

The ornamental design for an industrial robot as shown and described.

DESCRIPTION

FIG. 1 is a front view of an embodiment of a first industrial robot, showing my new design;

FIG. 2 is a back view of the first industrial robot;

FIG. 3 is a left view of the first industrial robot;

FIG. 4 is a right view of the first industrial robot;

FIG. 5 is a top view of the first industrial robot;

FIG. 6 is a bottom view of the first industrial robot;

FIG. 7 is a front, left, top perspective view of the first industrial robot;

FIG. 8 is a back, left, top perspective view of the first industrial robot;

FIG. 9 is a front, right, top perspective view of the first industrial robot;

FIG. 10 is a back, right, top perspective view of the first industrial robot;

FIG. 11 is a front, right, bottom perspective view of the first industrial robot;

FIG. 12 is a back, right, bottom perspective view of the first industrial robot;

FIG. 13 is a front view of an embodiment of a second industrial robot, showing my new design;

FIG. 14 is a back view of the second industrial robot;

FIG. 15 is a left view of the second industrial robot;

FIG. 16 is a right view of the second industrial robot;

FIG. 17 is a top view of the second industrial robot;

FIG. 18 is a bottom view of the second industrial robot;

FIG. 19 is a front, top perspective view of the second industrial robot; and,

FIG. 20 is a back, top perspective view of the second industrial robot.

1 Claim, 16 Drawing Sheets
